UNITED STATES PATENT OFFICE

ERNEST T. BECK, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A TABLE KNIFE OR SIMILAR ARTICLE

Application filed July 10, 1931. Serial No. 40,487. Term of patent 14 years.

To all whom it may concern:

Be it known that I, ERNEST T. BECK, a citizen of the United States, residing at Meriden, county of New Haven and State of Connecticut, have invented a new, original, and ornamental Design for a Table Knife or Similar Article, of which the following is a specification, reference being had to the accompanying drawings, forming a part thereof.

Fig. 1 is a plan view of a table knife or similar article illustrating my new design; and

Fig. 2 is a side view of the same.

The essential feature of the design is the general configuration of a table knife comprising a blade and handle of substantially the proportions and outline shown.

I claim:

The ornamental design for a table knife or similar article substantially as shown and described.

ERNEST T. BECK.
